UNITED STATES PATENT OFFICE.

JOHN M. HAIGIS, OF BRIDGEPORT, CONNECTICUT, ASSIGNOR TO JAMES D. FRARY, OF SAME PLACE.

HANDLE FOR POCKET CUTLERY.

SPECIFICATION forming part of Letters Patent No. 249,344, dated November 8, 1881.

Application filed September 24, 1881. (No model.)

To all whom it may concern:

Be it known that I, JOHN M. HAIGIS, of Bridgeport, in the county of Fairfield and State of Connecticut, have invented a new Improvement in Pocket Cutlery; and I do hereby declare the following, when taken in connection with the accompanying drawings and the letters of reference marked thereon, to be a full, clear, and exact description of the same, and which said drawings constitute part of this specification, and represent, in—

Figure 1, a side view; Fig. 2, a longitudinal central section through the blade-pivot, enlarged; Fig. 3, a transverse section at same point, enlarged.

This invention relates to an improvement in that class of pocket-knives in which a hard-metal lining is used with a wood or other outside scale, and a metal bolster cast thereon to aid in securing the scale to the lining; and it consists in the construction, as hereinafter described, and particularly recited in the claim.

A represents the blade; *a a*, the two sides of the lining; *b*, the rivet or pivot on which the blades turn. At the rivet on the outside of the lining a metal washer, *c*, is applied, the rivet being of sufficient length to extend through and secure the washers, as seen in Figs. 2 and 3. The edge of the washer is cut under, as seen in Fig. 3.

B is the covering, which may be of wood or

other suitable material, and comes up to the bolster-line, and at that end there is an undercut or recess formed in the outside of the scale, so that the bolster may extend therein. The 35 bolster is then cast in molds in the usual manner, and the metal flows into the recess on the outside of the scale, and also flows around the washer *c*, the latter causing it to be secured firmly to the lining. The overlapping of the 40 scale secures that end of the scale to the lining, but the overlapping or engaging of the scale with the bolster is not of my invention. The washers *c c* give an increased strength at the rivet, and enable the use of a thinner lining than could be otherwise employed. 45

Instead of the washer, the rivet may extend through each side and be struck down onto the lining, so as to form a projection on the surface corresponding to the washer and performing the same office. Therefore by the term "washer" I wish to be understood as embracing this equivalent.

I claim—

In a pocket-knife handle, the undercut 55 washer *c*, secured to the lining, and the bolster cast thereon, substantially as described.

JOHN. M. HAIGIS.
